UNITED STATES PATENT OFFICE.

OSWALD B. CARSON, OF BROOKLYN, NEW YORK, ASSIGNOR TO AMERICAN HARD RUBBER CO., OF NEW YORK, N. Y., A CORPORATION OF NEW YORK.

DISPLAY CARD FOR ADVERTISING PURPOSES.

Application filed May 10, 1923. Serial No. 638,140.

To all whom it may concern:

Be it known that I, OSWALD B. CARSON, a citizen of the United States, residing at Brooklyn, county of Kings, and State of New York, have invented new and useful Improvements in Display Cards for Advertising Purposes, of which the following is a full, clear, and exact description, such as will enable others skilled in the art to 10 which it appertains to make and use the same.

This invention relates to display cards, more particularly to a display card and to means for removably holding articles on said 15 display card with integral display holding means supplemented by a detachable fastener, made at small expense, that will removably hold in an attractive manner a variety of articles.

20 Referring to the drawings—

Figure 1 is a front view of a display card made in accordance with the present invention, arranged in the present instance to hold a plurality of combs.

25 Figure 2 is a sectional view on the line 2—2 of Figure 1.

Figure 3 is a back view of Figure 1.

Figure 4 is a sectional view on the line 4—4 of Figure 1.

30 In the drawings 1 designates a suitable display card preferably made of card-board or thick paper, although the same can be made of metal or other suitable material.

In the present instance and in accordance 35 with the present invention, the display card 1 is cut to provide one or more sets of overlapping tabs, each set of tabs comprises a tongue tab 2 and a grooved tab 3, as shown in Fig. 1. In the present instance the 40 tongue tab 2 is made relatively narrow, whereas the grooved tab 3 is made relatively broad, the tabs being preferably made to overlap each other at their free ends for approximately half their length so that the 45 same can be forced outward to permit for example the insertion of a comb 4.

In order to hold the comb in position the free end of the tongue tab 2 is provided with a slot 5 through which is inserted the 50 pointed end of an ordinary metal fastener

6 which passes, in the present instance, between the teeth of the comb, the split end of the fastener being bent into engagement with the comb as clearly shown in Fig. 3.

The metal fastener 6 is provided with a 55 relatively broad head and acts to overlap the free end of the tongue tab 2 so that it will engage the free end of the grooved tab 3 and hold it in position; when however the display card is made of relatively 60 thick card-board a small headed metal fastener 7 is all that is required to hold the article in position. In order to remove articles from the display card it is a simple 65 matter to remove the metal fastener.

In the present instance the grooved tab 3 is cut on either side for a considerable distance so as to provide a long flat base or bearing surface for the article to be held; this is important in the case of a comb as 70 it prevents tipping which acts to bend the teeth and set them if the comb remains in that position for any long period of time.

From the above description it will be seen that a plurality of sets of tabs can easily 75 be arranged on a display card to display articles such as combs and that the same can be readily secured thereto by means of a simple detachable metal fastener in a cheap and efficient manner.

80 While the invention has been described with particular reference to the details of construction the same is not to be considered as limited thereto as many changes can be made and still fall within the scope of the 85 invention set forth in the following claims.

What I claim is:—

1. In a display card, a tab of convex contour cut therefrom; an oppositely extending tab struck from the card its free 90 end being cut from the body of the first tab, the free ends of both tabs interengaging so that the first mentioned tab provides a shoulder for supporting the article to be displayed, the second tab providing means 95 for detachably affixing said article to the card.

2. In combination with a display card, a tab of convex contour cut therefrom; a second tab cut from the card its free end 100

being cut from the body of said first tab and interengaging therewith; fastening means carried by said second named tab adapted to overlap the first-named tab and 5 detachably affixed to the article to be displayed.

In testimony whereof I have signed this

specification in the presence of two subscribing witnesses.

OSWALD B. CARSON.
